UNITED STATES PATENT OFFICE.

HERMANN ARNDT, OF BERLIN, GERMANY, ASSIGNOR TO SIEMENS & HALSKE, AKTIENGESELLSCHAFT, OF SIEMENSSTADT, GERMANY, A CORPORATION OF GERMANY.

AUTOMATIC SECTION-BLOCK SYSTEM FOR RAILROADS.

Application filed September 9, 1925, Serial No. 55,380, and in Germany September 20, 1924.

- My invention relates to an automatic block signal system for railroads and particularly to systems employing light signals in which the operation of the signals takes place by means of alternating current relays which are controlled by the train itself. These relays are so designed that they receive their current partly from the rails of the respective block section and partly across an auxiliary phase, the flow of current being made dependent upon the state of the signals of the block section following next in the direction of travel. When the track is traversed by the train the track phase is short circuited through the train axles, the armature of the relay drops off and operates contacts by which the circuit leading to the go ahead lamps is interrupted and the circuit leading to the stop lamps is closed. When the train has left the block section 9 and has reached the next following block section which is insulated from the preceding one in any suitable manner, the relay of the block section 9 which the train has left receives current through the track phase. This current does, however, not suffice to attract the armature of the relay, as the relay is so designed that it can only be actuated if current is simultaneously present in the track phase and the auxiliary phase. If besides the stop lamps special track locks are also provided at the joint between two block sections which automatically prevent the overrunning of a stop signal, the development of the current through the stop lamps or the development of the current through the auxiliary phase may also be made dependent upon the closing of a contact which is controlled by the track lock itself. By the term "track lock" I mean to imply contrivances such as levers, detents, raised portions, or the like mounted adjacent to the track and actuated by the herein described initial blocking operation in any suitable manner, such that, in case the signal is set against the train, the contrivance is moved into such a position that it operates an element, for instance a lever, mounted on the train itself and by which in turn the brake mechanism is brought into action and the power supply shut off at the same time. Of course instead of such a mechanically operating track lock, inductive means may be mounted beside the track which are energized by the blocking current and which inductively bring about the power shut off and the setting of the brakes. All of these means are well known in the art and their detail construction is immaterial for the description of the present invention.
- According to my invention the stop lamps of a block section are connected in series with the auxiliary phase of the relay of the preceding block section. In this manner the same object is attained without the employment of auxiliary devices, such as relays, or other suitable means equivalent in their action.
- In the drawing an embodiment of my invention is illustrated diagrammatically.
- Referring to the drawing 1 is the relay for the block section 10 and 2 the relay for the block section 9. To each relay appertain the corresponding stop lamps 3 and go ahead lamps 4 and the contacts 5, 6 and 7 operated by the armature. 8 is the block line which connects the stop lamps of the block section 10 with the auxiliary phase of the rear relay 2 of the block section 9. 11 designates the earth line for which a special insulated line 80 may also be employed. 12 is the track lock for the block section 10 with the track lock contact 13 which is connected in series with the corresponding stop lamps 3 and the auxiliary phase of the rear relay 2. 14 designates the track lock for the block section 9 with the contact 15 appertaining thereto. 16 indicates the transformer which supplies the current across the block section 9 to the track phase 17 of the relay 2. 18 is the corresponding transformer for the preceding block section. 19 and 20 designate the transformers which supply the current for the respective lamps and the auxiliary phase of the respective relay. The transformers 95 receive their current from the common feed line 30. The figure represents the condition when the track is unoccupied. The relay 2 has attracted its armature and receives current from the transformer 16 through block 100.

section 9 to the track phase 17 on the one hand and on the other hand from the transformer 19 through line 21, earth, line 22, line 23, auxiliary phase 24, line 25, upper contact 6 of the attracted armature and return line 26 to the transformer. Simultaneously the go ahead lamps receive a current of lower voltage through an intermediate tap of the transformer, line 21, earth, line 27, upper contact 5 and return line 28. The condition of the following section is corresponding.

When a train has reached the block section 9 in the direction of travel indicated, the track phase 17 of the relay 2 is short circuited across the train axles, the armature of the relay drops off and interrupts at the upper contacts 5 and 6 the circuit to the go ahead lamps 4 and the auxiliary phase 24 and connects by means of the lower contact 6 the stop lamps 3 through the contact 15 also reversed by the relay of the track lock 14 which is in the locking position, with the transformer 19, contact 15 being also reversed by the relay 2. The current flows from the transformer 19 through line 26, lower contact 6, line 29, stop lamps 3, line 31, track lock contact 15, line 32, auxiliary phase of the rear relay not illustrated in the drawing, earth line 11, line 21 back into the transformer 19. When the train enters the block section 10 with its front portion, the track phase 33 of the relay 1 is short circuited. The armature of the relay drops off and interrupts the circuit to the auxiliary phase 34 and the go-ahead lamps 3 appertaining thereto, in the same manner as described with reference to relay 2. Simultaneously the track lock 12 and thus the contact 13 is reversed. The current from the transformer 20 now flows through line 35, the bottom relay contact 6, stop lamps 3, line 36, track lock contact 13, block line 8, bottom contact 7 of the relay 2, line 25, auxiliary phase 24, lines 23 and 22, earth line 11 and line 37 back to the transformer 20. According to the invention the stop lamps 3 of the block section 10 are thus connected in series with the auxiliary phase 24 of the rear relay 2 of the block section 9. The current in the auxiliary phase is, however, not sufficient to impart to the relay 2 the necessary power for operating the armature so that the stop lamps 3 of the block section 9 remain lighted so long as the block section 9 is occupied i. e. the track phase 17 is short circuited. As soon as the last axles of the train have left the block section 9 the track phase 17 of the relay 2 receives again current from the transformer 16. The armature 17 of the relay is attracted and thus, as already described, the current through the stop lamps is interrupted and led through the go ahead lamps.

65 By connecting the stop lamps of the block

section 10 with the track lock contact 13 and the auxiliary phase 24 in series, the result is attained that the relay 2 also can only be operated when the stop lamps of the block section 10 are lighted up and protect the train running into this block section. If the stop lamps of the block section 10 would not be lighted up owing to failure in closing the contacts or the like, the auxiliary phase 24 would receive no current, the track phase 75 17 alone would not suffice to operate the relay and the train which has run into the block section 10 would be protected by the stop lamps of the block section 9. If, however, as prescribed the track phase 17 and 80 the auxiliary phase 24 are traversed by current after the train has left the block section 9 the armature of the relay 2 is attracted, opens the circuit of the stop lamps, closes the go ahead circuit, releases the track lock 85 14 and simultaneously disconnects through the reversed contact 7 the auxiliary phase 24 from the block line 8 and the transformer 20 and connects it with the transformer 19. Hereby the track signal of the block section 90 9 has become independent from the stop lamps of the section 10.

In order to render the lighting of the stop lamps independent of the track lock contacts, the arrangement may according to the 95 invention be made so that if the track lock should remain in the go ahead position but the relays should already be short circuited, the stop lamps receive current through an earth contact of the track lock. The stop 100 current then flows from the line 35 through the stop lamps, line 36, contact 13, line 38, earth and line 37 back to the transformer 20.

In order to make the lighting of the stop lamps also independent of the contact 7 of 105 the rear relay 2, the stop lamps or at least one of them may be grounded through a resistance so that on failure of the contact 7 at least one of the stop lamps will be lighted. The current then flows from the transformer 110 20 through line 35, stop lamp 39, resistance 40, earth and return line 37 back to the transformer 20.

Various modifications may be made in my 115 invention and I desire that only such limitations shall be placed thereon as are imposed by the prior art or are specifically set forth in the appended claims.

I claim as my invention:

1. In a block signal system, in combination, a railroad track subdivided into individual block sections by insulating joints, a signalling device provided at the beginning of each of said sections and consisting of stop lamps and go ahead lamps, a relay 120 for controlling the circuits to said lamps and adapted to receive current on the one hand through the rails of the block section and on the other hand from an auxiliary phase which when the armature of said relay 125 130

has dropped off is connected in series with the stop lamps of the preceding block section, contacts upon the armature of said relay adapted to light up the stop and go ahead 5 lamps respectively by their make and break, a source of alternating current adapted to supply the current for operating said relay and said signal lamps, line conductors adapted to connect said source of current with 10 the two phases of the relay and the signal lamps, and line conductors between said signal lamps and said relay contacts.

2. In a block signal system, in combination, a railroad track subdivided into individual block sections by insulating joints, 15 a signalling device provided at the beginning of each of said sections and consisting of stop lamps and go ahead lamps, a relay for controlling the circuits to said lamps and 20 adapted to receive current on the one hand through the rails of the block section and on the other hand from an auxiliary phase which when the armature of said relay has 25 dropped off is connected in series with the stop lamps of the preceding block section, contacts upon the armature of said relay adapted to light up the stop and go ahead lamps respectively by their make and break, a source of alternating current adapted to 30 supply the current for operating said relay and said signal lamps, line conductors adapted to connect said source of current with the two phases of the relay and the signal lamps, line conductors between said 35 signal lamps and said relay contacts and a contact at said relay which after the attraction of the armature disconnects the auxiliary phase from the stop lamps of the following block section and connects them with 40 the source of current of the block section appertaining thereto.

3. In a block signal system, in combination, a railroad track subdivided into individual block sections by insulating joints, 45 a signalling device provided at the beginning of each of said sections and consisting of stop lamps and go ahead lamps, a relay for controlling the circuits to said lamps and adapted to receive current on the one hand through the rails of the block section and on the other hand from an auxiliary phase which when the armature of said relay has 50 dropped off is connected in series with the stop lamps of the preceding block section, contacts upon the armature of said relay adapted to light up the stop and go ahead lamps respectively by their make and break, a source of alternating current adapted to supply the current for operating 55 said relay and said signal lamps, line conductors adapted to connect said source of current with the two phases of the relay and the signal lamps, line conductors between said signal lamps and said relay contacts, a 60 contact at the said relay which after the 65

armature has been attracted disconnects the auxiliary phase from the stop lamps of the following block section and connects it with the source of current of the block section appertaining thereto and a track lock at the 70 beginning of the block section adapted to close in its stop position by means of a contact, the current traversing the corresponding stop lamps and the auxiliary phase of 75 the relay located in the rear.

4. In a block signal system, in combination, a railroad track subdivided into individual block sections by insulating joints, a signalling device provided at the beginning of each of said sections and consisting of stop lamps and go ahead lamps, a relay for controlling the circuits to said lamps and adapted to receive current on the one hand through the rails of the block section and on the other hand from an auxiliary phase 80 which when the armature of said relay has dropped off is connected in series with the stop lamps of the preceding block section, contacts upon the armature of said relay adapted to light up the stop and go ahead 85 lamps respectively by their make and break, a source of alternating current adapted to supply the current for operating said relay and said signal lamps, line conductors adapted to connect said source of current with the two phases of the relay and the signal lamps, line conductors between said signal lamps and said relay contacts, a contact at the said 90 relay which after the armature has been attracted disconnects the auxiliary phase from the stop lamps of the following block section and connects it with the source of current of the block section appertaining thereto, a track lock at the beginning of the block section adapted to close in its stop 95 position by means of a contact the current traversing the corresponding stop lamps and the auxiliary phase of the relay located in the rear and a grounding contact on the track lock which in the go ahead position of said 100 lock is adapted to ground the stop lamps appertaining thereto.

5. In a block signal system, in combination, a railroad track subdivided into individual block sections by insulating joints, a signalling device provided at the beginning of each of said sections and consisting of stop lamps and go ahead lamps, a relay for controlling the circuits to said lamps and adapted to receive current on the one hand through the rails of the block section and on the other hand from an auxiliary phase which when the armature of said relay has dropped off is connected in series with the stop lamps of the preceding block section, 115 contacts upon the armature of said relay adapted to light up the stop and go ahead lamps respectively by their make and break, a source of alternating current adapted to supply the current for operating said relay and said signal lamps, line conductors adapted to connect said source of current with the two phases of the relay and the signal lamps, line conductors between said signal lamps and said relay contacts, a 120 contact at the said relay which after the 125

and said signal lamps, line conductors adapted to connect said source of current with the two phases of the relay and the signal lamps, line conductors between said signal lamps and said relay contacts, a contact at the said relay which after the armature has been attracted disconnects the auxiliary

phase from the stop lamps of the following block section and connects it with the source of current of the block section appertaining thereto and a grounding contact in the circuit of one of said stop lamps. ¹⁰

In testimony whereof I affix my signature.
HERMANN ARNDT.
